[57] CLAIM

The ornamental design for a wakeboard binding, as shown and described.

DESCRIPTION

FIG. 1 is a top perspective view of a pair of wakeboard bindings showing our new design, the broken line illustration of wakeboard forms no part of the claimed design; FIG. 2 is a top plan view of one of wakeboard bindings of FIG. 1;

FIG. 3 is a side elevational view of FIG. 2, with the other side the same;

FIG. 4 is a rear elevational view of FIG. 2;

FIG. 5 is a front elevational view of FIG. 2;

FIG. 6 is a bottom plan view of FIG. 2; and,

FIG. 7 is a perspective view of a second embodiment of the wakeboard, the sole difference from the first embodiment being in the pull-on strap attached to the rear of wakeboard.
